JOHN MAINLAND AND SOREN CHRISTIAN NYBERG, OF LA PORTE, INDIANA, ASSIGNORS TO THE ADVANCE-RUMELY COMPANY, OF LA PORTE, INDIANA, A CORPORATION OF INDIANA.

FEEDING DEVICE FOR THRASHING MACHINES.

Application filed November 26, 1924. Serial No. 752,300.

This invention relates to a feeding device and assembly for separators, and is adaptable to many types of machines generally described as separators and thrashers. Such machines are adapted to operate on many types of grains and their products, and this invention is applicable to such machines generally.

This invention is illustrated more or less diagrammatically in the accompanying drawings, wherein:

Figure 1 is a partial side elevation of the feeder end of the separator;

Figure 2 is a side elevation showing on an enlarged scale the same end of the separator on the opposite side;

Figure 3 is a vertical fore and aft section showing in section that portion of the machine shown in elevation in Figure 2;

Figure 4 is a sectional view showing on an enlarged scale the upper part of the feeder hood and assembly which appears in Figure 3, showing carrier and hood raised.

Figure 5 is a generally horizontal cross section taken on line 5—5 of Figures 1 and 2;

Figure 6 is a vertical cross section taken on the line 6—6 of Figures 2 and 3;

Figure 7 is a vertical cross section taken on the line 7—7 of Figure 2;

Figure 8 is an elevation of the spreader cylinder partially shown in section in Figure 7;

Figure 9 is a detail vertical cross section taken on line 9—9 of Figure 1 showing in part the supporting and mounting for the feeder.

Like parts are indicated by like characters throughout.

A is a separator housing which generally encloses the parts of a separator machine.

A¹ is the forward end of this housing which encloses a portion of the feeding mechanism, the spreader cylinder, the main cylinder, the concave and other essential parts of the machine.

The forward end of the separator is carried on an axle A² on wheels A³. The details of these will not be described. A⁴ is one section of an adjustable two-part carrier. It has hinged to it another section A⁵. A⁶

A⁶ are adjustable braces for supporting the carrier at each side. They have screwed in their lower ends adjusting screws A⁷ which carry bevel gears A⁸. These gears mesh with a second pair of bevel gears A⁹

which are carried by a shaft which has on it a crank handle A¹⁰. By means of the rotation of the handle the screws may be caused to rotate and so may be moved in and out to adjust the height of the carrier.

Mounted within the carrier is a pair of chains B. These chains carry at proper intervals slats or bars B¹ and are supported and driven by sprockets B² on a shaft B³. By means of these chains and the slats, material to be thrashed is fed to the thrashing mechanism of the separator. This consists of a number of separate assemblies. By reference particularly to Figure 3 these thrashing parts may be seen.

C is a crank shaft carried in bearing blocks C¹ which blocks have lateral projections C². Pivoted to each of these projections is a hanger C³ which at its lower end is provided with a plurality of perforations C⁴. The hanger C³ lies against an outwardly bent slotted strap C⁵ which is secured to the side of the carrier A⁴. Positioned in one of the perforations C⁴ and extending through the slot of the slotted strap C⁵ and having its head located inside this strap is an adjusting bolt C⁶. Since the bolt lies in a slot in the strap C⁵ some relative movement of the upper part of the separator housing can take place without binding or interfering with the carrier and this construction is provided to permit this movement.

The crank shaft C may be provided with any number of throws C⁷. There is shown in the accompanying drawings three such throws. Upon each of these is mounted a band cutter.

This includes the following elements, and on each of the crank throws is mounted a bearing block D. This block is preferably made of two wooden sections as is shown herewith, and these sections are fastened together by metal plates D¹ and bolts D².

There is provided a hole D³ within which oil or other lubricant may be located, and an oil cup or other similar device D⁴ may be used. Extending rearwardly from each of the blocks D is a pair of ears D⁵.

Fastened to each of these ears is a cutter bar D⁶ having a forwardly bent portion D⁷ on which are mounted a plurality of cutting knives D⁸. At its upper end the bar D⁶ is pivotally fastened to a link D⁹ which in turn is pivoted at D¹⁰.

Fastened between each pair of ears D⁵ and

in the rear of the bars D⁶ is a feeder pan supporting member E which at one end is carried on a bolt E¹ and at the other end on a link E² which is pivoted on an arm E³ fixed 5 on a shaft E⁴. Fastened below the member E is the feeder pan E⁵. This pan has extending lengthwise a plurality of rows of toothed blades E⁶, and extending laterally adjacent its lower end one or more rows of 10 toothed blades E⁷.

Mounted partially below and to the right of the feeder pans as shown in Figure 3 is a spreading cylinder. This cylinder is carried on a shaft F and is made up of two 15 end members F¹ a central member F², and a plurality of longitudinal members F³, each of which has extending outwardly from it a number of fingers F⁴. Located on the inner side of the casing A¹ and adjacent the 20 end of the spreader cylinder and overhanging the ends is an inwardly extending flange F⁵. On one end of the shaft F is a driving pulley F⁶. At each end the shaft is carried on adjusting bearings which permit the 25 bearings to be aligned during assembly to compensate for irregularities in manufacture. As shown in the drawings each of the bearings is the same and therefore the section view shown in Figure 7 serves for both 30 ends.

Reinforcing the bearing is a laterally extending channel G. Surrounding the shaft and within the area prescribed by the channel G is a bearing supporting block G¹ having a generally spherically shaped cavity G² within it. Penetrating within this cavity and corresponding in shape to it is one part G³ of the ball bearing holding assembly. Secured to this by means of bolts G⁴ 35 is a second ball bearing holding piece G⁵. Between the pieces G³ and G⁵ is located a ball bearing having one race between the two pieces and the other fixed on the shaft F. Located between the members G G¹ and G⁵ 40 and the shaft F are bearing spacing collars or sleeves G⁶. G⁷ is a retaining ring adjustably secured on the shaft, by means of which the collars are retained generally in position.

H is the governor collar freely mounted 50 on the shaft F and having a beveled surface H¹ at one end and a groove H² adjacent its other end. H³ is a second governor collar fixed on the shaft F, carrying governor balls H⁴ H⁴ pivoted respectively at H⁵ H⁵ and 55 having arms H⁶ which extend within the grooves H² of the collar H. Springs H⁷ tend to retain the balls in relative position shown in Figures 2 and 7.

I is a main cylinder shaft upon which is 60 mounted the cylinder I¹ which carries the teeth or fingers I². The cylinder I¹ operates in conjunction with a concave I³ which has fingers I⁴ so spaced that the fingers I² of the cylinder I¹ pass between them. The concave is adjustably mounted on a rotatable 65

shaft I⁵ which carries an eccentric I⁶ by means of which the concave may be raised and lowered.

J is a retarder shaft which carries upon it a plurality of retarder fingers J¹ which are adapted to rotate with it. Between the retarder fingers are guards J². These guards in the form here shown are metallic loops extending once about the shaft J and having their ends fastened to a bar J³. 75

Beneath the retarder is a shaker pan K. This pan has on it a number of laterally extending steps or flights K¹, and adjacent its lower end one or more rows of laterally extending teeth K². At its lower end the shaker pan K is carried on a plate K³ upon which it slides back and forth when the separator is in operation. Beneath the pan K are one or more members K⁴ each of which carries a bearing block K⁵ in which is journaled the rock shaft K⁶. This shaft has fixed upon it an arm K⁷ which is connected at its outer end to a pitman K⁸, which at its upper end is pivoted to a gear wheel K⁹. 80 85 90

Pivoted on the feeder end of the separator and carrying with it a crank shaft of the band cutter, and one end of the feeder pan and supported from the inner end of the carrier is a hood L. It is reinforced by means of a U-shaped member L¹ which at its inner end is pivoted about the shaft L² and has a cross brace bar L³ near the inner ends. The inner ends of the U-shaped member L¹ is provided with eyes L⁴ which are positioned 100 about the bearings for the bearing housing of the shaft L². The member L is provided with outwardly flaring portions L⁴ L⁴.

There is provided in order to avoid breakage and clogging a pair of automatic stop devices and also a friction clutch. The automatic stop devices are shown particularly in Figure 2. The roller M which appears in Figures 2 and 7 is carried in the forked end of a lever arm M¹. At its other end this arm has a stop hook M² which is adapted to engage a lug M³ fixed to the shaft B³ and rotating with it. When the thrashing parts of the separator are not moving rapidly enough to operate properly upon the material to be thrashed, the governor balls will not move far enough out to move the roller M. As the machine, however, gains speed the governor balls move farther out the collar H moves to the right as shown in Figure 7; the roller M is moved outward, and the lever arm M¹ is raised and the hook M² moves out of contact with the lug M³ on the feeder driving shaft B³ and material to be thrashed is then delivered into the machine. 115 120 125

The amount of material which can pass into the machine is regulated by the size of the opening between the carrier and the feeder pans. In order to vary the size of this opening the rear end of the feeder pan 130

may be adjusted and may be raised or lowered. This is done by rotating the shaft E⁴. The shaft has fixed upon it an adjusting handle N. Free to move upon the shaft E⁴ is an adjusting plate N¹ having an arcuate slot N² formed in it, and provided with a raised serrated flange N³ adjoining the slot. The adjusting lever N is provided with cooperating and a correspondingly serrated raised flange N⁴. A bolt N⁵ extends through the slot and through a perforation in the handle N. At its outer end is a thumb nut N⁶. Fastened to the outer end of the adjusting plate N¹ is a rod O which passes through a perforated block O¹ and has on it a collar O². When the handle fixed on the shaft E⁴ has been adjusted suitably with relation to the plate N¹, the parts are fixed in the chosen position, and the weight of the feeder pans pulling downward on the members E³ moves the shaft E⁴ downward and thus moves the handle N and the plate N¹, and with this the rod O until the collar O² contacts the block O¹ and then the parts remain in the position shown, the weight of the rear end of the feeder pans being carried upon the collar through the linkage above described. About the rod O and beneath the collar is a helical spring O³. The compression of this spring may be adjusted by a threaded collar O⁴ which surrounds the rod. Mounted for movement upon the rod O is one end of the lever arm O⁵, the arm being pivoted at O⁶. Beneath the lever arm O⁵ is a spring O⁷ and beneath this a collar O⁸. The opposite end of the lever O⁵ extends toward the shaft B³ and normally lies above and out of the path of the lug M³.

When for any reason an excessive quantity of material comes to or accumulates in the throat of the machine, that is between the carrier and the feeder pans, the rear end of the feeder pans will be raised, rotating the shaft E⁴ and through it moving upward the rod O against the resistance of the spring O³. This movement carries with it the right hand end of the lever O⁵ as shown in Figure 2 and correspondingly depresses the other end of this lever, throwing it into the path of the hook M² which it contacts and so stops the movement of the feeder and prevents further clogging. If this movement took place when the lever O⁵ was exactly above the lug M³ breakage might occur and to avoid this the spring O⁷ is provided which permits some yielding of the lever O⁵ without breakage; and the moment the lug M³ has passed from under the lever, the latter will be restored to its normal position and will engage the lug upon its next revolution, so stopping the machinery and preventing further clogging.

I shall now describe the driving connections. On one end of the cylinder shaft I is a pulley P which is adapted to be driven

by a belt P¹ from a tractor or any other suitable power source. At the other end of the shaft I is a second pulley P² which extends outwardly beyond the housing A¹, on the same side of the machine and on the shaft F is a pulley P³. On the shaft L² is a large pulley P⁴, and mounted on the pivoted lever P⁵ is a tightener pulley P⁶. Surrounding all of these pulleys and driving them all from the pulley P² is a belt P⁷. Fixed on the shaft L² just inside the pulley P⁴ is a sprocket P⁸ which engages and is connected by means of a chain P⁹ to a sprocket P¹⁰ on the crank shaft C. At the end of the shaft L² opposite from the pulley P⁴ is keyed a pinion P¹¹ and a sprocket P¹². The pinion P¹¹ meshes with the gear K⁹ and through it moves the pitman K⁸ and the rock shaft to which it is connected.

Carried in the mounting X is a stud X¹. Mounted on and adapted to rotate about this stud is a sleeve P¹³ which has fixed upon it a pinion P¹⁴ and is provided with an outwardly extending flange P¹⁵. Mounted about the sleeve is a sprocket wheel P¹⁶ which is normally held against the flange P¹⁵ and is driven by the chain P²⁵ from the sprocket P¹². On the other side of said flange is an engaging disc P¹⁷. The sprocket P¹⁶ and the disc P¹⁷ are held together by means of bolts P¹⁸, which have about them blocks of rubber P¹⁹ or other yielding material. By means of this construction the sprocket wheel P¹⁶ is held normally fixed with relation to the flange P¹⁵, but slippage is possible, and this assembly constitutes in effect a friction clutch.

The pinion P¹⁴ engages with the gear P²⁰ on the shaft B³ and thus completes the drive through to the carrier shaft. On the opposite end of the shaft B³ is a sprocket wheel P²¹. P²² is a sprocket on one end of the shaft J on the same side of the machine as the sprocket P²¹ on the shaft B³. This shaft J is driven through a chain P²³ from the sprocket P²¹, and thus the retarder is driven from the carrier.

Q is a link mounted in the upper end of the lever P⁵. It passes through a perforated retaining member Q¹ and has about it a helical spring Q². In the outer end of the link Q is an adjusting screw Q³ by means of which the degree of compression on the spring may be varied. It is normally such as to hold the parts in the position shown in Figure 1, and adjustment may be made so as to make the proper degree of pull on the belt P⁷.

R is a worm wheel on the rotatable shaft I⁵. It meshes with a worm R¹ which may be rotated by the handle R². By means of this arrangement the shaft I⁵ is moved so as to raise and lower the cam I⁶ and thus vary the adjustment of the concave I³.

Although we have shown an operative de-

vice, still it will be obvious that many changes might be made in size, shape and arrangement of parts without departing materially from the spirit of our invention; and we wish therefore that our showing be taken as in a sense diagrammatic.

The use and operation of our invention are as follows:

When the machine is to be used for thrashing grain or other suitable material, the parts are generally in the position shown in Figure 1. The carrier is raised or lowered to any suitable height by means of the adjustable support beneath it and the hood L with the parts which it carries is raised or lowered with reference to the carrier so as to adjust the size of the throat opening above the carrier belt and beneath the band cutters and feeder pans. The concave is also adjusted to a suitable position, and when these adjustments have been accomplished the machine is set in operation.

As power is first applied the cylinders commence rotating, but the carrier sprocket shaft does not rotate. This is because the stop M^2 is engaging the lug M^3 attached to that shaft. The governor which acts upon the roller M is so proportioned and adjusted that when the cylinder and other parts have attained a sufficient speed for proper thrashing, the balls spread, and thus the roller M is moved and the hook M^2 slips out of contact with the lug M^3 and the carrier shaft commences to rotate and the carrier to move and feed material to the machine for thrashing.

When for any reason the speed of rotation of the cylinder and the speed of movement of the other parts which are driven in relation to the cylinder falls below the necessary point for satisfactory operation, the governor slows down and again permits the point M^2 to engage the lug M^3 to stop the carrier and to prevent the feeding of additional material into the thrashing parts, thus preventing the further clogging and jamming of the machine.

This operation of stopping feeding of material to the thrashing parts when the speed of their movement falls below the necessary limit, is not for all purposes sufficiently rapid to prevent clogging. Therefore another and quicker acting stop is provided. When for any reason clogging takes place, the material is not passed downward beyond the spreader, the retarder, the cylinder and the concave rapidly enough and thus it accumulates in this general area and builds up, and as more material comes it builds higher, crowding up under the feeder pans. When this crowding has occurred to a sufficient degree, the feeder pans are raised thus rotating the shaft from which their lower ends are supported, and when the shaft moves the adjusting plate N^1 which

is fixed with relation to the shaft moves also, carrying upward the part O and rotating the lever O^5 so that its end comes in contact with the lug M^3 and stops rotation of the shaft B^3 , thus preventing further feeding of material into the thrashing zone. This action takes place very rapidly and is the first to cause stopping of the machine. When the clogging has been remedied and the machine is again in condition for operating, the stop which is operated by movement of the feeder pans is of course freed. As soon as material is removed from under them so that they are no longer forced up, this stop goes out of operation, but the other stop which is operated by the governor first has come into operation and so prevents starting of the feeding mechanism until after the thrashing parts have attained the necessary speed to carry out proper thrash- 75 80 85 90 95 100 105 110 115 120 125 130

When the machine is first started, as above noted, the feeding carrier does not operate, but the other parts do. At this time the friction clutch shown in Figure 6 in detail operates to permit rotation of the other parts of the machine while the feeding mechanism which is normally driven together with them does not operate. During this period of operation the friction clutch slips. When sufficient speed has been gained by the thrashing parts and the governor operates to permit rotation of the carrier, the clutch no longer slips and the parts are all driven together. When for any reason the operation of the machine is stopped by either of the automatic stops, the clutch again slips and thus this clutch slips when the carrier is not rotated, but when it is rotating does not slip, and all of the normally rotating parts are operated together.

We claim:

1. In combination in a thrasher, thrashing means, and means for feeding material thereto, an automatic stop adapted to prevent feeding to said thrashing means until the same has reached sufficient speed for thrashing, and a second automatic stop adapted to stop the movement of said feeding means when clogging takes place within the thrasher, said first mentioned stop being governor controlled and operated in response to the speed of rotation of the thrashing means.

2. In combination in a thrasher, thrashing means, and means for feeding material thereto, an automatic stop adapted to prevent feeding to said thrashing means until the same has reached sufficient speed for thrashing, and a second automatic stop adapted to stop the movement of said feeding means when clogging takes place within the thrasher, said first mentioned stop being governor controlled and operated in response to the speed of rotation of the thrashing means,

in combination with a member located within the feeding area and adapted when clogging takes place to be displaced to operate said second stop.

3. In combination in a thrasher, thrashing means, and means for feeding material thereto, an automatic stop adapted to prevent feeding to said thrashing means until the same has reached sufficient speed for thrashing, and a second automatic stop adapted to stop the movement of said feeding means when clogging takes place within the thrasher, said first mentioned stop being governor controlled and operated in response to the speed of rotation of the thrashing means, in combination with a member located within the feeding area and adapted when clogging takes place to be displaced to operate said second stop, said second stop adapted to be moved automatically out of operative position when the clogging material has been removed to permit return movement of the member which operates it.

4. In a thrasher, in combination a feed carrier assembly and moving elements in addition to the feed carrier adapted to act upon material fed to the thrasher, the two associated so that adjustment of the carrier moves said elements.

5. In a thrasher, in combination a feed carrier assembly and moving elements adapted to act upon material fed to the thrasher, the two associated so that adjustment of the carrier moves said elements, said elements being mounted in fixed relation with each other, and in combination with means permitting relative adjustment between them and the carrier.

6. In a thrasher, in combination a feed carrier assembly and moving elements adapted to act upon material fed to the thrasher, the two associated so that adjustment of the carrier moves said elements, there being a loose link connection between the carrier and said elements adapted to permit slight relative movement of one without causing movement of the other.

7. In a thrasher, in combination a feed carrier assembly and moving elements adapted to act upon material fed to the thrasher, the two associated so that adjustment of the carrier moves said elements, said elements being mounted in fixed relation with each other, and in combination with means permitting relative adjustment between them and the carrier, there being a loose link connection between the carrier and said elements adapted to permit slight relative movement of one without causing movement of the other.

8. In combination with a thrasher, a feeding mechanism and a pivoted supporting frame, said frame carrying certain of the thrashing mechanisms, and being mounted and connected to said feeding mechanism

so that movement of the latter moves the former.

9. In combination with a thrasher, a feeding mechanism and a pivoted supporting frame, said frame carrying certain of the thrashing mechanisms, and being mounted and connected to said feeding mechanism so that movement of the latter moves the former, and means for relatively adjusting the two so that the supporting frame may be selectively adjusted with relation to the feeding means.

10. In combination with a thrasher, a feeding mechanism and a pivoted supporting frame, said frame carrying certain of the thrashing mechanisms, and being mounted and connected to said feeding mechanism so that movement of the latter moves the former, and a loose link connection between the two adapted to permit limited relative movement of one without causing movement of the other.

11. In combination with a thrasher, a feeding mechanism and a pivoted supporting frame, said frame carrying certain of the thrashing mechanisms, and being mounted and connected to said feeding mechanism so that movement of the latter moves the former, and means for relatively adjusting the two so that the supporting frame may be selectively adjusted with relation to the feeding means, and a loose link connection between the two adapted to permit limited relative movement of one without causing movement of the other.

12. In combination in a thrasher, thrashing parts and feeding parts, the same adapted normally to be driven together, in combination therewith a clutch arrangement whereby the feeding mechanism may be stopped while the thrashing mechanism continues to operate, in combination with an automatic stop adapted to prevent movement of said feeding means while permitting through the slipping of said clutch, movement of said thrashing mechanism.

13. In combination in a thrasher, thrashing parts and feeding parts, the same adapted normally to be driven together, in combination therewith an automatic clutch arrangement whereby the feeding mechanism may be stopped while the thrashing mechanism continues to operate, in combination with an automatic stop adapted to prevent movement of said feeding means while permitting, thru the slipping of said clutch, movement of said thrashing mechanism.

14. In combination in a thrasher, thrashing parts and feeding parts, the same adapted normally to be driven together, in combination therewith a clutch arrangement whereby the feeding mechanism may be stopped while the thrashing mechanism continues to operate, in combination with a plurality of automatic stops adapted to prevent

- movement of said feeding means while permitting, through the slipping of said clutch, movement of said thrashing mechanism.
15. In combination in a thrasher, thrashing parts and feeding parts, the same adapted normally to be driven together, in combination therewith an automatic clutch arrangement whereby the feeding mechanism may be stopped while the thrashing mechanism continues to operate, in combination with a plurality of automatic stops adapted to prevent movement of said feeding means while permitting, through the slipping of the clutch, movement of said thrashing mechanism.
16. In combination in a thrasher, thrashing parts and feeding parts, the same adapted normally to be driven together, in combination therewith an automatic clutch arrangement whereby the feeding mechanism may be stopped while the thrashing mechanism continues to operate, in combination with a plurality of automatic stops adapted to prevent movement of said feeding means while permitting through the slipping of the clutch, movement of said thrashing mechanism, one of said stops adapted to operate automatically when the thrashing mechanism after having been started slows down below the necessary speed for thrashing.
17. In combination in a thrasher, thrashing parts and feeding parts, the same adapted normally to be driven together, in combination therewith an automatic clutch arrangement whereby the feeding mechanism may be stopped while the thrashing mechanism continues to operate, in combination with a plurality of automatic stops adapted to prevent movement of said feeding means while permitting, through the slipping of the clutch, movement of said thrashing mechanism, one of said stops adapted to prevent movement of the feeding mechanism until the thrashing mechanism has attained sufficient speed, the other of said stops adapted to operate automatically when the thrashing mechanism after having been started slows down below the necessary speed for thrashing.
18. In a thrashing machine a pivotally mounted carrier trough, a band cutter adjacent the discharge end thereof, means for automatically raising and lowering it as the inclination of the carrier is changed to maintain the distance between it and the carrier constant.
19. In a thrashing machine a pivotally mounted carrier trough, a band cutter adjacent the discharge end thereof, means for automatically raising and lowering it as the inclination of the carrier is changed to maintain the distance between it and the carrier constant, means for separately adjusting the mouth of the cutter above the carrier.
20. In a thrashing machine a pivotally mounted carrier trough, a band cutter adjacent the discharge end thereof, means for automatically raising and lowering it as the inclination of the carrier is changed to maintain the distance between it and the carrier constant, the cutter being free to move away from the carrier when an excess of material is fed to it by the carrier.
21. In a thrashing machine a pivotally mounted carrier trough, a band cutter adjacent the discharge end thereof, means for automatically raising and lowering it as the inclination of the carrier is changed to maintain the distance between it and the carrier constant, means for separately adjusting the mouth of the cutter above the carrier, the cutter being free to move away from the carrier when an excess of material is fed to it by the carrier.
22. The combination with a feeder for thrashing machines and the like of means for conveying a continuous stream of material thereto, means located above the stream for cutting the bands, pushing the material through the feeder and spreading and distributing it as it is discharged to the thrashing cylinder there being a pivotal connection between the band cutting means and the means for pushing the material through the feeder.
23. The combination with a feeder for thrashing machines and the like of means for conveying a continuous stream of material thereto, means located above the stream for cutting the bands, pushing the material through the feeder and a spreading cylinder in opposition to the thrashing cylinder there being a pivotal connection between the band cutting means and the means for pushing the material through the feeder.
24. The combination with a feeder for thrashing machines and the like of means for conveying a continuous stream of material thereto, means located above the stream for cutting the bands, pushing the material through the feeder and spreading and distributing it as it is discharged to the thrashing cylinder, and means engaging the underside of the stream for retarding the flow of material and for stopping the flow of the underside of the stream when the feed is stopped there being a pivotal connection between the band cutting means and the means for pushing the material through the feeder.
25. The combination with a feeder for thrashing machines and the like of means for conveying a continuous stream of material thereto, means located above the stream for cutting the bands, pushing the material through the feeder and a spreading cylinder in opposition to the thrashing cylinder, and means engaging the underside of the stream for retarding the flow of material and for stopping the flow of the underside of the stream when the feed is stopped there.

being a pivotal connection between the band cutting means and the means for pushing the material through the feeder.

26. In a thrashing machine, a plurality of pusher fish backs adjacent the discharge end thereof and means for raising and lowering the supports therefor as the inclination of the carrier is changed to maintain constant the width of the throat between the pushers and the carrier.

27. The process of feeding material to a thrashing machine which consists in conveying thereto a continuous stream of material cutting the bands on the upper side thereof, engaging the upper side thereof and pushing it forward into the thrashing machine and engaging the material on the upper side thereof and spreading and distributing it as it is discharged to the thrashing cylinder and in engaging the stream of material from beneath to retard its flow and stopping the flow of the underside of the stream when the feed is stopped there being a pivotal connection between the band cutting means and the means for pushing the material through the feeder.

28. In a thrashing machine a pivotally mounted carrier, a band cutter mounted for movement therewith to maintain a constant distance between them independent of variation in the angular relation, pusher fish backs adapted to move with the band cutter to maintain a constant width of throat, a distributing cylinder adapted to engage the upper surface of the stream of material brought in by the carrier there being a pivotal connection between the band cutting means and the means for pushing the material through the feeder.

29. In a thrashing machine a pivotally mounted carrier, a band cutter mounted for movement therewith to maintain a constant distance between them independent of variation in the angular relation, pusher fish backs adapted to move with the band cutter to maintain a constant width of throat, a distributing cylinder adapted to engage the upper surface of the stream of material brought in by the carrier, a retarder adapted to retard the flow of the underside of the stream of material and means for stopping the movement of the retarder when

the feed of the carrier is stopped there being a pivotal connection between the band cutting means and the means for pushing the material through the feeder.

30. In a thrashing machine a pivotally mounted carrier, a band cutter mounted for movement therewith to maintain a constant distance between them independent of variation in the angular relation, pusher fish backs adapted to move with the band cutter to maintain a constant width of throat, a distributing cylinder adapted to engage the upper surface of the stream of material brought in by the carrier, a retarder adapted to retard the flow of the underside of the stream of material and means for stopping the movement of the retarder when the feed of the carrier is stopped, means operative when the speed of the thrashing machine falls below a predetermined point for stopping the feed of the carrier there being a pivotal connection between the band cutting means and the means for pushing the material through the feeder.

31. In a thrashing machine a pivotally mounted carrier, a band cutter mounted for movement therewith to maintain a constant distance between them independent of variation in the angular relation, pusher fish backs adapted to move with the band cutter to maintain a constant width of throat, a distributing cylinder adapted to engage the upper surface of the stream of material brought in by the carrier, a retarder adapted to retard the flow of the underside of the stream of material and means for stopping the movement of the retarder when the feed of the carrier is stopped, means operative when the speed of the thrashing machine falls below a predetermined point for stopping the feed of the carrier, and means operative when the material fed through the throat exceeds a predetermined amount for stopping the feed of the carrier there being a pivotal connection between the band cutting means and the means for pushing the material through the feeder.

Signed at Chicago, county of Cook and State of Illinois this 8th day of November, 1924.

JOHN MAINLAND.
